UNITED STATES PATENT OFFICE.

EUGENE A. DE MAY, OF RICHMOND, TEXAS.

CAR-COUPING.

SPECIFICATION forming part of Letters Patent No. 367,197, dated July 26, 1887.

Application filed June 3, 1887. Serial No. 240,118. (No model.)

To all whom it may concern:

Be it known that I, EUGENE A. DE MAY, of Richmond, in the county of Fort Bend and State of Texas, have invented a new and Improved Car-Coupling, of which the following is a specification, reference being had to the annexed drawings, forming a part thereof, in which—

Figure 1 is a side elevation of my improved car-coupling. Fig. 2 is a plan view showing one of the coupling-hooks withdrawn and the other in the position of use; and Fig. 3 is a perspective view of the latch for holding the coupling-hook out of position for engagement with another similar hook.

Similar letters of reference indicate corresponding parts in all the figures.

The object of my invention is to provide a simple and effective coupling for use upon freight-cars, for automatically coupling the cars.

My invention consists in a shaft journaled at its lower end in the ordinary draw-bar and at its upper end in a bracket secured to the top 25 of the car, and in the combination therewith of a brace attached to the draw-bar, adapted to support the lower end of said shaft, a hook placed between the brace and the draw-bar, and a spring surrounding the shaft and arranged to hold the shaft and hook normally in the position of use.

It also further consists in the combination, with the hook, of a spring-actuated uncoupling-rod extending through a bracket at the side of the car and a retaining-latch pivoted to the car and adapted to hold the said rod in a retracted position.

The draw-bar A is of the ordinary construction, and is attached to the timbers of the car 40 B in the usual way. The hole a in the draw-bar, which usually receives the coupling-pin, is enlarged to receive the shaft C, which extends downward through the draw-bar and upward above the top of the bar B, where it is 45 journaled in a bracket, D, secured to the top of the car, and the upper end of the shaft is provided with a hand-wheel, E.

Upon the shaft C, between the bracket D and draw-bar A, is secured a collar, F, between 50 which and the draw-bar is placed a spiral spring, G, which is capable of lifting and sus-

taining the shaft C and parts carried thereby. The lower end of the shaft C is journaled in a brace, H, which is offset and secured to the underside of the draw-bar. Between the brace 55 H and the draw-bar A a hook, I, is secured on the shaft C. The point of the said hook projects beyond the end of the draw-bar, and is provided with a beveled face, b. Upon the back of the hook is formed an apertured ear, 60 c, which receives a hook, d, formed on the end of the rod J. The rod J extends through an apertured bracket, K, attached to the end of the ear, at the corner thereof, and is provided with a loop, e, forming a handle by which the 65 rod may be operated. Between the bracket K and the ear c, and upon the rod J, is placed a spiral spring, f, which tends to press the hook forward into the position of use.

At the side of the car is pivoted a latch, L, 70 formed with an arm, g, carrying on its free end a half-sleeve, h, which is capable of shutting down over the outer end of the rod J, between the loop e and the bracket K, thus holding the rod J and hook I in a retracted position, so that the said hook will not engage the corresponding hook of an adjacent car. 75

When it is desired to put the coupling into position for use, the latch L is withdrawn from the rod J, when the spring f pushes the hook 80 I forward, so that it may engage with the corresponding hook of the adjacent car.

When it is desired to prevent the engagement of the hooks I while the train is in motion, and it is inconvenient to operate the 85 hooks by the rods J, the trainman at the top of the car can prevent the engagement of the hooks by pushing downward the shaft C against the pressure of the spring G, thereby bringing the hook I out of the path of the hook of the 90 adjoining car.

Having thus fully described my invention, I claim as new and desire to secure by Letters Patent—

1. In a car-coupling, the combination, with 95 the draw-bar A, of the brace H, secured to the draw-bar, the shaft C, journaled in the draw-bar and in the brace, the bracket D, supporting the upper end of the shaft C, the hook I, attached to the shaft C and provided with the apertured ear c, the rod J, connected with the ear, the bracket K, secured to the car, and the 100

spring *f*, surrounding the rod *J*, abutting against the bracket *K* and arranged to press the coupling-hook *I* forward, substantially as described.

5 2. In a car-coupling, the combination of the draw-bar *A*, the bracket *D*, the shaft *C*, journaled in the draw-bar and bracket and provided with the collar *F*, the spring *G*, placed between the collar and the draw-bar, the hook *I*, secured to the shaft *C*, between the brace *H* and draw-bar *A*, and provided with the apertured ear *c* and beveled end *b*, the rod *J*, pro-

vided with the hook *d*, engaging the ear *c*, and having the loop *e* formed on the outer end thereof, the bracket *K*, supporting the rod *J*, 15 the spring *f*, placed upon the rod *J* between the bracket *K* and the ear *c*, and the latch *L*, provided with the half-sleeve *h*, adapted to engage the rod *J*, substantially as described.

EUGENE A. DE MAY.
